(57) **CLAIM**

The ornamental design for a mobile kitchen cart, as shown and described.

DESCRIPTION

FIG. 1 shows an elevational perspective view of the mobile kitchen cart.

FIG. 2 is a front view of the mobile kitchen cart.

FIG. 3 is a rear view of the mobile kitchen cart.

FIG. 4 is a left side view of the mobile kitchen cart.

FIG. 5 is a right side view of the mobile kitchen cart.

FIG. 6 is a top view of the mobile kitchen cart; and,

FIG. 7 is a bottom view of the mobile kitchen cart.

The broken line showing of the casters and line on the side bars is included for the purpose of illustrating environment and forms no part of the claimed design.
